CLAIM

The ornamental design for an electronic percussion, as shown and described.

DESCRIPTION

The patent or application file contains at least one drawing executed in color. Copies of this patent or patent publication with color drawing(s) will be provided by the Office upon request and payment of the necessary fee.

FIG. 1 is a right side perspective view of a first embodiment of an electronic percussion showing my new design;

FIG. 2 is a left side perspective view thereof;

FIG. 3 is a top plan view thereof;

FIG. 4 is an enlarged view of the portion indicated by lines 4-4 in FIG. 1;

FIG. 5 is an enlarged view of the portion indicated by lines 5-5 in FIG. 2;

FIG. 6 is an enlarged view of the portion indicated by lines 6-6 in FIG. 3;

FIG. 7 is a right side perspective view of a second embodiment of an electronic percussion showing my new design;

FIG. 8 is a left side perspective view thereof;

FIG. 9 is a top plan view thereof;

FIG. 10 is an enlarged view of the portion indicated by lines 10-10 in FIG. 7;

FIG. 11 is an enlarged view of the portion indicated by lines 11-11 in FIG. 8; and,

FIG. 12 is an enlarged view of the portion indicated by lines 12-12 in FIG. 9.

The features shown in broken lines in the drawings depict environmental subject matter only and form no part of the claimed design. The dot-dashed lines denote the boundary of the claim, and form no part of the claimed design.
